CLAIM

The ornamental design for an implant delivery device as shown and described.

DESCRIPTION

FIG. 1 is a top view of an implant delivery device according to an embodiment of the present invention.

FIG. 2 is a bottom view of the implant delivery device depicted in FIG. 1.

FIG. 3 is a top perspective view of the implant delivery device depicted in FIG. 1 illustrating the implant delivery device in its intended use with a prosthetic implant shown in broken lines.

FIG. 4 is a top perspective view of the implant delivery device depicted in FIG. 3 illustrating the implant delivery device partially folded over the prosthetic implant.

FIG. 5 is a top perspective view of the implant delivery device depicted in FIG. 4 illustrating the implant delivery device partially folded over the prosthetic implant.

FIG. 6 is a top perspective view of the implant delivery device depicted in FIG. 5 illustrating the implant delivery device completely folded over the prosthetic implant; and, FIG. 7 is a top perspective view of the implant delivery device depicted in FIG. 6 illustrating the implant delivery device in its intended use of delivering the prosthetic implant into a surgical incision.

The broken lines in the drawings illustrate portions of the implant delivery device that form no part of the claimed design. The broken lines illustrating the human hands and human figure in FIG. 7 are for the purpose of showing environment associated with the claimed design in a state of use and form no part of the claimed design.
